DESIGN.

T. G. HAWKES.

ORNAMENTATION OF GLASSWARE, &c.

No. ^D18,268.

Patented Apr. 24, 1888

UNITED STATES PATENT OFFICE.

THOMAS G. HAWKES, OF CORNING, NEW YORK.

DESIGN FOR THE ORNAMENTATION OF GLASSWARE, &c.

SPECIFICATION forming part of Design No. 18,268, dated April 24, 1888.

Application filed January 9, 1888. Serial No. 260,231. Term of patent 7 years.

To all whom it may concern:

Be it known that I, THOMAS G. HAWKES, a citizen of the United States, residing at Corning, in the county of Steuben and State of New York, have invented and produced a new and original Design for the Ornamentation of Glass and other Ware, of which the following is a specification, reference being had to the accompanying photograph, forming part thereof.

10 I show my design applied as an ornament to a glass dish.

My design consists of intersecting arcs of circles 1, seven in number, arranged to form a seven-pointed star, with triangular figures at the points. In the center of this star is formed a rosette, 2, while the triangular figures at the several points of the star are made with roughened surfaces 3. The portions of the arcs of the circle projecting beyond the star have between them ovate figures 4, obtuse at the outer ends, which in the present instance form part of the edge of the dish. Between these ovate figures, and extending from between the points

of the star, are banner-like figures 5, the main body of which is made up of three portions, 6, 25 7, and 8. The portions 6 7 are rhomboidal in shape, being bounded by straight lines 9. The portion 8 is covered by a fan-shaped figure, and between the two rhomboids 6 7 are smaller fan-shaped figures, 10 10. Within each of the 30 rhomboids are two figures, 11 12, both rhomboidal in shape, one having radiating lines and the other having a roughened or barred surface. Between the two there stretch from angle to angle along the main axis of the rhomboid a number of angular figures, 13.

Having thus described my invention, the following is what I claim as new therein and desire to secure by Letters Patent:

The design for the ornamentation of glass 40 and other ware, substantially as herein described and shown.

THOMAS G. HAWKES.
